LOOSE-LEAF RECORD BOOK

Bernard Klein and Barney A. Heimbinder,
New York, N. Y.

Application July 25, 1938, Serial No. 221,130

2 Claims. (Cl. 129—20)

This invention relates to new and useful improvements in a loose-leaf record book.

More specifically, the invention proposes the construction of a loose-leaf record book having a plurality of leaves each consisting of a pair of superimposed sheets secured together along their edges and formed with a plurality of superimposed openings arranged in spaced horizontal and vertical lines for receiving extension portions 10 formed on one side of a card adapted to be mounted upon said leaf.

Heretofore devices of this type were constructed by attaching notched strips along the length of a sheet at spaced positions with relation to each other and provided with a plurality of cards having notched portions engageable with the notches formed in said strips for holding the cards in position upon the sheet.

Still further it is proposed to form the openings of a triangular shape with a right angle at the junction of the altitude and the base with the hypotenuses of each vertical row of openings directed away from each other in a manner to permit the extension portions to be easily engaged therethrough and provide a four point locking arrangement to prevent relative movement between the card and sheet.

A further object of this invention is to form the openings in a substantially flat sheet in such a manner that the card superimposed thereon will at all times remain in substantially flat position with relation to the sheet to prevent the same from bending inwards at the center and provide a smooth surface to make it easy to write upon the cards.

Still further it is proposed to form the extension portion on one side of the card in such a manner that it will be capable of acting as a hinge to permit the card to be easily swung backwards without becoming detached from the leaf to expose the cards located therebeneath.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a perspective view of a loose-leaf record book constructed according to this invention.

Fig. 2 is a perspective view of the book in an open position and exposing the cards.

Fig. 3 is a perspective view of one of the completed leaves per se.

Fig. 4 is a view similar to Fig. 3 illustrating one of the steps in the manufacture of the leaf.

Fig. 5 is a sectional view taken on the line 5—5 of Fig. 4.

Fig. 6 is a sectional view on the line 6—6 of Fig. 4.

Fig. 7 is a sectional view on the line 7—7 of Fig. 6.

Fig. 8 is a perspective view of one of the cards per se. 10

The loose-leaf record book, according to this invention, comprises a loose-leaf cover 10 having a plurality of pairs of rings 11 upon which a plurality of leaves are adapted to be mounted in such a manner that each of the leaves may be turned for exposing the cards 12 mounted thereon. Each of the leaves is constructed in an identical manner and comprises a pair of superimposed sheets 13 secured together along their outer edges. A binding strip 14 is engaged over three edge portions of the sheets 13 and is held in position by stitches 15 engaging therethrough to hold the superimposed sheets together as a unit. The sheets 13 are formed with a plurality of superimposed openings 16 arranged in spaced vertical lines along the length of the sheets 13. A sheet of spacer material 17 is inserted between the adjacent faces of the sheets 13 through the open edge portions thereof for keeping the rows of openings 16 formed in one of the sheets spaced from the openings 16 formed in the other of the sheets. A second binding strip 14^a is engaged over the fourth edge portion of the sheets 13 for completely encasing the spacer material 17. 15 20 25 30 35 40 45 50 55

The openings 16 are triangular in shape with their right angles located at the junction of the altitude and the base. The hypotenuses of the triangles in each row of openings are directed away from each other, as clearly shown in Figs. 40 3 and 4. The openings 16 in the sheets 13 are arranged in pairs with respect to horizontal points along the vertical lines in which they are also positioned.

A card 12 for each of the horizontal pairs of 45 openings 16 has an extension portion 12^a formed on one side thereof. The ends of the extension portion 12^a are formed with outwardly directed elements 12^{aa} which are adapted to be engaged with each horizontal pair of openings for maintaining the cards in position on the leaves. The outwardly directed elements are easily engaged with relation to each horizontal pair of openings by first slipping one of the outwardly directed elements 12^{aa} beneath the hypotenuse of one of the 50 55

- openings and then slightly bending the card to contract the end portions 12^{aa} to permit the other end portion 12^a to be slipped beneath the hypotenuse of the opposite opening 16 of the other vertical row.
- Each of the cards 12 is formed with a line of perforations 18 extending along the width thereof and located between the extension portion 12^a and the card proper for permitting the card to be folded backwards along this line to permit the extension portion 12^a to act as a hinge and remain in position with relation to the leaf to permit any number of cards to be folded rearwards to expose the face of any one card mounted upon the leaf.
- The construction of the outwardly directed elements 12^{aa} is of a width substantially equal to the altitude of the openings 16 so that the top of the extensions 12^{aa} will bear against the junction between the altitude and hypotenuse of the openings 16 to form a pair of lock points on each side of said card. While the top edge is engaging against the said junction the bottom of the extensions will engage against the junction between the base and the hypotenuse of each of the openings to form a bottom pair of lock points on each side of said card. Thus each card has four lock points as clearly shown in Fig. 2, two lock points being located on each side of said extension portion for preventing any relative movement either vertically or horizontally between the cards 12 and the leaves on which they are mounted.

One of the side edge portions of each of the leaves, namely the one having the binding strip 14^a, is formed with a plurality of openings 19 which are adapted to be engaged by the pairs of rings 11 for holding the leaves in position with relation thereto. The construction of the rings 11 is conventional for permitting the leaves to be removed and inserted into the cover 10.

In the drawing the pairs of superimposed sheets 13 have been shown constructed from Celluloid or similar material, but we do not wish to be limited to this specific construction as it is also possible to construct these sheets from relatively stiff cardboard or other similar material.

A rib 20 is embossed between the adjacent openings 16, as shown in Figs. 6 and 7, for stiffening the material located between the openings to prevent the leaf from collapsing under weights placed on the edges thereof. These ribs 20 are

embossed in the sheets after the leaves have been completed.

While we have illustrated and described the preferred embodiments of our invention, it is to be understood that we do not limit ourselves to the precise constructions herein disclosed and the right is reserved to all changes and modifications coming within the scope of the invention as defined in the appended claims.

Having thus described our invention, what we claim as new, and desire to secure by United States Letters Patent is:

1. In a loose-leaf record book, a leaf, comprising a pair of superimposed sheets secured together along their edges and formed with a plurality of superimposed openings arranged in vertical lines spaced from each other, a sheet between said sheets for separating said openings, said openings being formed in said sheets in pairs with respect to horizontal points along said vertical lines, a card for each of said pairs of openings and each card having at one side an extension formed with outwardly directed end elements engaging into the openings of one horizontal pair of openings for holding said card in position on said leaf, and ribs embossed in said leaf between the openings of each vertical row of openings for reinforcing said leaf.

2. In a loose-leaf record book, a leaf, comprising a pair of superimposed sheets secured together along their edges and formed with a plurality of superimposed openings arranged in vertical lines spaced from each other, a sheet between said sheets for separating said openings, said openings being formed in said sheets in pairs with respect to horizontal points along said vertical lines, a card for each of said pairs of openings and each card having at one side an extension formed with outwardly directed end elements engaging into the openings of one horizontal pair of openings for holding said card in position on said leaf, and ribs embossed in said leaf between the openings of each vertical row of openings for reinforcing said leaf, said ribs formed in one of said superimposed sheets being concaved and resting against the sheet inserted between said sheets for raising the edges of said openings for facilitating the engagement of said end elements into said openings.
